Attorneys

UNITED STATES PATENT OFFICE.

WILLIAM FRANKLIN KNELL, OF DETROIT, MICHIGAN.

FLUSHING VALVE.

Application filed March 14, 1923. Serial No. 625,005.

To all whom it may concern:

Be it known that I, WILLIAM F. KNELL, citizen of the United States, residing at Detroit, in the county of Wayne and State of Michigan, have invented certain new and useful Improvements in Flushing Valves; and I hereby declare that the following is a full, clear, and exact description thereof, reference being had to the accompanying drawings, which form part of this specification.

This invention is a novel flushing valve for water closets and the like, and its principal object is to provide a flushing valve by which the closet may be flushed directly from a water supply pipe without necessitating the use of a tank or reservoir; and which will be effective in its operation; and will not require frequent adjusting and repairing.

Another object of the invention is to dispense with the usual tank or flushing reservoir and its accompanying mechanical valve controlling devices. Further, to provide an efficient flushing apparatus, simple in construction, small, compact, and easy to install, and which will not be liable to get out of order.

The present application is an improvement over my application for U. S. Letters Patent on flushing valve, filed April 11, 1922, Serial No. 551,495.

In the accompanying drawings I have illustrated one practical embodiment of the invention and will describe the same with reference thereto, to enable others to understand and use the same; and in the appended claims summarize the novel features of construction, and novel combinations of parts, for all of which protection is desired.

In said drawings:

Fig. 1 is a vertical section through the valve showing the parts in closed position in full lines, and the valve partly open in dotted lines.

Fig. 2 is a section similar to Fig. 1 showing the parts in the position assumed when the valve is opened.

Fig. 3 is a transverse section on the line 3—3 Fig. 1.

In the construction shown in the drawings the operative parts of the valve are arranged within a cylindrical casing 1, which is provided with a hollow T 1^a projecting from one side a little below its center, which T is preferably internally threaded to receive the

end of a water supply pipe S, indicated in Fig. 1.

The top of casing 1 is preferably closed by a cap 2, externally threaded at 2^a to engage the internal threads 1^b at the top of casing 1, and this cap 2 is preferably provided with a hexagonal projection 2^d adapted for engagement with a wrench, or the like, whereby cap 2 may be screwed onto or off of the casing 1. Cap 2 may be provided with a recess 2^c in its inner side, as indicated in Figs. 1 and 2, to accommodate the upper end 8^a of the valve stem 8, hereinafter referred to. A washer 2^b is preferably inserted between the cap and the top of the casing, as shown.

The bottom of the casing 1 is preferably internally threaded to receive the externally threaded end 3^b of a lower cylindrical casing member 3 containing the outlet port. Casings 1 and 3 are preferably made of brass or other non-corrosive metal and may be nickel plated or otherwise finished on their exteriors. Member 3 is partly closed at its upper or inner end by an interior circumferential flange 3^c leaving an opening or port 3^d at the center thereof. The upper outer edges of member 3 are preferably formed to make a circumferential shoulder 3^a above which is an externally threaded part 3^b adapted to engage the internal threads at the lower end of casing 1. A washer 1^e may be placed between casing 1 and member 3, as shown. The lower part of member 3 is exteriorly threaded for engagement with the closet bowl or other member to be flushed.

Within the member 3, are bearings 3^f, adapted to receive a horizontal rock shaft 3^g upon which is mounted a finger 3^h for unseating the valves, as hereinafter explained, finger 3^h being secured to said shaft in any desired manner, as by a set screw. At the point where the shaft 3^g passes through the member 3, a stuffing box 3^k may be provided to prevent water escaping from the casing around the shaft, and shaft 3^g may be operated by a handle 3^l on the outer end thereof.

Within the casing, on the axis thereof, is a tube 3^x which is preferably externally threaded on its lower end to engage threads in the port 3^d of the member 3, tube 3^x extending upwardly from the member 3, as shown, slightly above the opening in the T 1^a of casing 1. Tube 3^x is somewhat smaller

in diameter than the interior diameter of casing 1, and the upper edge of the tube is preferably machined to form a smooth finish or valve seat for the piston valve 4, hereinafter explained.

Within the tube 3^x, on the vertical axis of the casing 1, is a tubular valve stem 5, on the upper end of which, above the top of tube 3^x, is mounted between two threaded 10 collars 4^a, 4^b, a piston valve 4, the top of said stem 5 being preferably flush with the top surface of the upper collar 4^a. Stem 5 extends down within the tube 3^x to within a short distance of the lower end of 15 said tube, and mounted on the lower end of said stem 5 is a spider 7, slidably engaging the inner walls of the tube 3^x for the purpose of aligning said stem within the tube 3^x. The upper end of said stem 5 is aligned 20 by the piston valve 4, engaging the walls of the casing 1 above the tube 3^x.

Within the casing 1 is a piston valve 4 mounted on the upper end of stem 5, which may be of any suitable construction, being 25 slideable in said casing 1 and dividing the casing into an upper and lower chamber, which chambers vary in volume according to the position and movement of the piston valve. As shown, piston valve 4 comprises 30 an inverted cup 4^x of leather or any suitable material, which is securely mounted on the upper end of stem 5 between a metal disk 4^c, and a thick leather disk 4^f of smaller diameter than disk 4^c, said leather disk 4^f 35 forming the valve for closing the upper end of tube 3^x. Below disk 4^f is a fibre disk 4^g of somewhat smaller diameter than the inside diameter of tube 3^x, and disks 4^c, 4^x, 4^f, and 4^g are all mounted on the stem 5 between collars 4^a and 4^b, the downwardly 40 flanged portions of disk 4^x engaging the sides of the casing 1 to prevent passage of water thereby. An aperture 4^e, extending through the piston valve 4 outside the tube 45 3^x permits water to pass slowly from the lower to the upper casing chamber.

Extending through the tubular valve stem 5 extending above and below same and slideable therein, is a tube 8, which is preferably 50 provided with a disk like valve 8^a on its upper end. A washer 8^b is preferably placed on stem 8 below head 8^a and is adapted to seat upon the upper face of collar 4^a, preventing leakage of water from the upper 55 chamber into the tube 8 when said valve 8^a is closed.

In the upper end of tube 8 below the valve 8^a are provided ports 8^e, through which the water in the upper chamber may pass into 60 the tube 8 and to the closet bowl, when the valve 8^a is unseated, as shown in dotted lines in Fig. 1.

Tube 8 is normally held in the depressed 65 position relative to stem 5 (as shown in full lines in Fig. 1) by means of a spring 8^c

mounted on the lower end of tube 8 below stem 5 and confined between the spider 7 and on stem 5 and a collar 8^d mounted on the lower end of the rod 8.

70

Operation.

In the normal position of the parts, as shown in Fig. 1, water from pipe S fills the lower casing chamber, also the upper chamber by passing through the aperture 4^e in the piston valve 4, while valve 4^f closes the upper end of tube 3^x, and the valve 8^a is held seated by the action of the spring 8^c, as above described.

In order to flush the bowl, handle 3^m is raised and when it reaches the position shown in dotted lines in Fig. 1, the finger 3^h will raise the tube 8 in the stem 5, unseating valve 8^a and allowing the water in the upper chamber to pass through the ports 8^e 80 down through the tube 8, and into the closet bowl. The fluid pressure above the piston valve 4 being thus decreased by the escape of water from the upper chamber, allows the piston valve 4 to rise (under the pressure of the water entering from pipe S) to the approximate position shown in Fig. 2, allowing the water from the pipe S to pass over the upper edge of tube 3^x and into the closet bowl, which operation will continue 85 as long as valve 8^a is unseated.

When handle 3^m is released spring 8^c again seats valve 8^a upon collar 4^a, and there then being no outlet for the water of the upper chamber, said upper chamber 100 gradually fills with water through aperture 4^e, forcing piston valve 4 downward tending to seat valve 4^f upon the top of tube 3^x to close same.

The water passing out through the tube 3^x creates a downward pressure on the top of spider 7 which also tends to cause the valve 4^f to seat upon the top of tube 3^x to stop the flow of water, however the piston 105 will only descend as fast as the upper chamber is filled by the passage of water through the aperture 4^e.

When the valve 4^f is seated the upper and lower chambers are again filled with water and the valve is ready for re-use. The valve is self-regulating regardless of the water pressure in pipe S, and the speed of operation thereof is controlled by the size of the aperture 4^e in the piston valve 4. If the pressure in the pipe S is high water will 110 be forced through the aperture 4^e more quickly than if the pressure is low, and the valve 4^f can not close the tube 3^x until the upper chamber is refilled by the passage of water through the aperture 4^e. In locations 115 where the water pressure of the mains is extremely high a smaller water supply pipe S could be used advantageously.

What I claim is:

1. A flushing apparatus comprising a 120

- member having a fluid inlet and a fluid outlet; a tube surrounding the outlet, a piston valve adapted to normally close the upper end of the tube, and to divide the interior 5 of the member into upper and lower chambers; an aperture through the piston valve exterior to said tube for permitting a restricted flow of water past the piston from the lower to the upper chamber; a tubular stem within said tube depending from said piston valve; a release valve adapted to seat on the upper face of said piston valve; a second tubular stem depending from said release valve, and adapted to slide within said 10 first mentioned tubular stem; a guide on the lower end of said first mentioned tubular stem adapted to engage the walls of said tube; a rock shaft mounted in the member; an actuating lever on said shaft exterior to 15 said member; a stuffing box in said member, walls around said shaft; and a finger on said shaft adapted to engage the lower end of said second tubular stem to raise said release valve and vent said upper chamber, 20 whereby the outlet valve will be opened and will remain open until the upper chamber is again filled with water passing through the said aperture, whereupon the main outlet valve will be seated.
- 25 2. In a flushing valve, a cylindrical casing having an inlet and an outlet port; a tube surrounding said outlet portion, and extending above the inlet port, the upper end thereof forming a valve seat; a valve 30 for closing said outlet port; a piston on said valve dividing the casing into upper and lower chambers; a tubular stem within said tube depending from said valve; a guide on the lower end of said stem slidably engaging the walls of said tube; an aperture 35 through said piston for admitting water to pass into the upper chamber past said piston; a release valve adapted to seat on the upper face of said piston; a second tubular stem 40 slidable within the first mentioned tubular stem and extending through said piston and below the lower end of said first mentioned tubular stem; a port in the upper end of said second tubular stem for venting the upper chamber when said stem and release valve are raised; spring means for normally holding said second tubular stem in position to close the port and release valve therein, and means for actuating said second 45 tubular stem to vent the water above said piston through the second tubular stem and below said outlet valve.
- 50 3. In a flushing valve, a cylindrical casing having an inlet port in its side and an outlet port in its bottom; a tube surrounding said outlet portion and extending above the inlet port, the upper end thereof forming the outlet valve seat; a valve for clos- 55 ing said outlet port; a piston on said valve dividing the casing into upper and lower chambers; a tubular stem within said tube depending from said valve; a guide on the lower end of said stem slidably engaging the walls of said tube; an aperture through said piston for permitting a restricted flow of water from the lower to the upper chamber past said piston; a second tubular valve stem closed at its upper end slidable within the first mentioned tubular stem and extending through said piston and below the lower end of said first mentioned tubular stem; a port in the upper end of the walls of said second tubular stem for venting the upper chamber when said stem is raised; a spring on the lower end of said second stem interposed between the lower ends of said tubular stems for normally holding said second stem in position to close the port therein; and means for actuating said second tubular stem to vent the water in the upper chamber through the second tubular stem, whereby the outlet valve will open and will remain open until the upper chamber is again filled with water.
- 60 4. In a flushing valve, a cylindrical casing; an inlet in the side thereof; an outlet in the bottom thereof; a tube around said outlet and extending upwardly in the casing above the inlet; the upper edge of said tube forming an outlet valve seat; a valve for closing said outlet valve; a piston connected with said valve and dividing the interior of the casing into an upper and lower chamber; a tubular stem depending from said piston and disposed within said tubular member; a guide on the lower end of said stem slidably engaging said tube; said piston having an aperture therein exterior to the tube to admit a restricted flow of water from the lower to the upper chamber; a second tubular stem closed on its upper end and extending through said first mentioned stem and projecting above and below said outlet valve, and having ports therein near its upper end to vent the water from the upper chamber and discharge same through the second tubular stem below the outlet valve when the second stem is raised; spring means between the said tubular stems for normally holding said second tubular stem in position to close the ports therein; a rock shaft mounted in the casing below the lower end of said second tubular stem; a lever for actuating said rock shaft; and a finger on said rock shaft for actuating said second tubular stem to open the ports against the action of the spring, substantially as described.
- 65 In testimony that I claim the foregoing as my own, I affix my signature.

WILLIAM FRANKLIN KNELL.
